UNITED STATES PATENT OFFICE

JAMES S. SWANN, OF CHICAGO, ILLINOIS, ASSIGNOR TO UNION METAL PRODUCTS COMPANY, OF CHICAGO, ILLINOIS, A CORPORATION OF DELAWARE

HOPPER DOOR

Application filed May 18, 1931. Serial No. 538,060.

My invention relates to the construction of railway cars of the dumping or drop bottom type, such as hopper cars, hopper gondola cars, drop bottom or general service 5 gondola cars or the like, having a door forming a part of the load retaining means, which door is provided with hinges adjacent one of its edges and is capable of being dropped or swung open to discharge the load. Any 10 means of raising the door to the closed position and any means for locking and releasing the door may be employed with my door.

The door may also be used as an end door or end gate of a "mill type gondola" wherein 15 the sides of the car are rigid but the end walls are hinged to the car at their lower margins so that they can be dropped or lowered to a horizontal position to permit the car to be used for transporting articles longer than a 20 single car, such as fabricated girders and beams, poles, pipes, etc.

I prefer to make the door of cast metal because a better distribution of the metal for 25 strength requirements can be obtained without the use of separate fixtures, and furthermore, cast metal has greater resistance to corrosion than rolled steel.

Another object of the invention is to provide a door of cast metal formed and shaped 30 so that it will not be deformed by warping when cooling, and furthermore, will eliminate shrinkage cracks and internal stresses.

Another object of the invention is to reinforce the body portion of the door by stiffening elements which extend from the hinge butts on one side of the door to the supporting means on the opposite side of the door, which elements are deflected from straight 35 lines and connected adjacent their middles by a stiffening member, wherein the stiffening elements and the stiffening member are so positioned as to divide the area of the body of the door into substantially equal areas so 40 that any part of the body of the door will be in close proximity to the reinforcing element.

In the drawings:

Figs. 1, 2 and 3 show the preferred form 50 of my invention wherein the reinforcing element and members comprise corrugations

wherein Figs. 2 and 3 are sections on lines 2-2 and 3-3 respectively of Fig. 1.

Figs. 4, 5 and 6 show the door formed with reinforcing ribs wherein Figs. 5 and 6 are sections on lines 5-5 and 6-6 respectively 55 of Fig. 4.

The door comprises a body 2 with spaced apart hinge butts 3 at one side of the body and spaced apart supports 4 at the opposite side of the body and a stiffening element 6 extending from each hinge butt 3 to the support 4 on the opposite side of the door and a stiffening member 8 connecting the middles of the elements 6. The stiffening elements 6 being deflected from straight lines whereby 60 the portions 10 of the body between the elements and the member and the portions 12 between the elements and the ends of the door are of substantially equal area.

In order to reinforce the perimeter of the 70 door I preferably provide a corrugation 14 adjacent each side of the door which merges into a preferably depending continuous flange 16 extending around all sides of the door. The reinforcing elements 6 merge into 75 this corrugation adjacent the hinge butt 3 and support 4 respectively.

I preferably make these doors of cast metal, as cast metal has a greater resistance to corrosion than rolled metallic plates. However, 80 the form shown in Figs. 1, 2 and 3 may be made of a rolled metallic plate pressed between reciprocating dies.

Figs. 4, 5 and 6 show my device made of cast metal wherein the body 30 is provided 85 with preferably integral hinge butts 31 on one side of the door and preferably integral supports 32 on the opposite side thereof. The reinforcing elements 34 merge into the flange 35 adjacent the perimeter of the door 90 and the reinforcing member 37 connects the middles of the reinforcing elements 34 which are shown as deflected from straight lines, so that the portions 38 and 40 are of substantial 95 ly equal area. The several elements preferably vary in depth according to the stresses imposed upon them.

The accompanying drawings illustrate the preferred form of the invention, though it is 100 to be understood that the invention is not

limited to the exact details of construction shown and described, as it is obvious that various modifications thereof, within the scope of the claims, will occur to persons skilled in the art.

I claim:

1. A door forming part of the load retaining means of a railway car comprising a body, spaced apart hinge butts on one side of said body, spaced apart supports on the opposite side of said body, said body provided with a stiffening element extending from each hinge butt to the support on the opposite side of the door, and a stiffening member connecting the middles of said elements, said stiffening elements being deflected from straight lines whereby the portions of the body between the elements and the member and between the elements and the ends of the door are of substantially equal area.
2. A door forming part of the load retaining means of a railway car comprising a body provided with flanges adjacent the sides and ends thereof, spaced apart hinge butts on one side of said body, spaced apart supports on the opposite side of said body extending from each hinge butt to the support on the opposite side of the door, and a stiffening member connecting the middles of said elements, said stiffening elements being deflected from straight lines whereby the portions of the body between the elements and the member and between the elements and the ends of the door are of substantially equal area.
3. A door forming part of the load retaining means of a railway car formed from a flat metallic plate comprising a body provided with a continuous corrugation adjacent the sides and ends thereof which merge into a continuous flange at the sides and ends of the door, spaced apart hinge butts on one side of said body, spaced apart supports on the opposite side of said body, said body provided with a stiffening corrugated element extending from each hinge butt to the support on the opposite side of the door and a stiffening corrugated member connecting the middles of said elements, said stiffening elements being deflected from straight lines whereby the portions of the body between the elements and the member and between the elements and the ends of the door are of substantially equal area.

JAMES S. SWANN.
